CREASE HOLDING MEANS FOR GARMENTS

David Segelin and Solomon Segelin,
Rochester, N. Y.

Application November 26, 1934, Serial No. 754,694

2 Claims. (Cl. 2—231)

This invention relates to means for preserving the crease in trousers and other garments and has for its object to provide means which indefinitely hold the crease in garments in their natural form.

A further object of this invention is to so incorporate the holding means in the garments that it will hold the crease without affecting the pliability or any other quality of the fabric.

These and other objects and attendant advantages of this invention will become more readily apparent from the detailed description thereof which follows, reference being had to the accompanying drawing in which

Figure 1 is a front elevation of a pair of trousers.

Figure 2 is an enlarged perspective view of a creased portion of the trousers illustrating the manner in which the crease holding means is applied thereto.

Figure 3 is an enlarged sectional view of the creased portion of the trousers, the section being taken on the line 3x—3x of Figure 1.

In the several figures of the drawing like reference numerals indicate like parts.

The subject matter of our present invention comprises means whereby any tension on the fabric of garments can be entirely eliminated from any creased portion thereof in order to preserve the crease ironed into the fabric for an indefinite period.

This is accomplished by the use of a tape 1 which has a marginal portion on each side sewed to the inside of the garment behind the crease 2 formed therein. These marginal portions are thus flatly secured to the inside of the garment in spaced relation to the crease so that the free portion of the width of the tape provides a brace 3 between the inner sides of the crease and at a suitable distance from the inner edge thereof. Any tension on the fabric from either side of the crease will thus be transmitted from one side of the crease to the other by the brace 3 and keep the tension away from the crease and prevent the crease from pulling out.

As illustrated in Figures 2 and 3 the edges of the tape 1 are suitably sewed to the inside of the fabric so that the stitching is not visible on the outside of the garment. Furthermore only such stitching is preferably used as will provide a non-rigid seam that will not impair the pliability of the fabric or at least very little so that the presence of the tape 1 will not be noticeable on the outside of the garment.

The tape 1 may be of any desired fabric which

will provide a non-rigid brace so that it can adapt itself to any angular position of the crease within the limits to which it is held thereby. It is also desirable although not absolutely necessary to locate the brace behind the crease a distance that will keep the tape from completely filling the inside thereof when the garment or a portion of it is completely collapsed along the crease in order that the crease can be sharply ironed into the fabric and the brace cannot hold the extreme point of the crease expanded and make it appear as a rounded ridge instead of a pointed crease.

The tape is made up of a non-yielding or substantially non-yielding fabric to provide a brace between the sides of the inside of the crease so that the crease cannot be pulled out by lateral tension, as above described, as well as keep the fabric from stretching along the line of the crease and thus prevent a distortion of the crease by the longitudinal stretching of it. The action of the knee of a person wearing trousers provided with our crease holding means will therefore have no effect on the crease as the same is kept from stretching in any direction.

While moisture applied to the fabric may affect the crease to a small extent, the fact that the crease is held and cannot be stretched when moist will keep it in such condition that it can be quickly and easily ironed back by anyone into its original form.

We claim:

1. A garment provided with a crease maintained indefinitely by a strip of flexible material having a substantial edge portion of each side thereof overlapping the garment fabric along the inside of said crease and secured thereto by suitable stitching so as to lie flatly thereagainst whereby the intermediate portion of said strip is spaced from and serves to limit expansion of said crease and the edge portions of said strip serve as permanent hinge connections between said intermediate portion and the garment fabric.

2. A garment provided with a crease maintained indefinitely by a strip of flexible material having a substantial edge portion of each side thereof overlapping the garment fabric along the inside of said crease and secured thereto by an overedge blind stitch so as to lie flatly thereagainst whereby the intermediate portion of said strip is spaced from and serves to limit expansion of said crease and the edge portions of said strip serve as permanent hinge connections between said intermediate portion and the garment fabric.

DAVID SEGELIN.
